CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

RAZOR-STROPPER.

1,095,218.

Specification of Letters Patent.

Patented May 5, 1914.

Application filed July 14, 1913. Serial No. 778,834.

To all whom it may concern:

Be it known that I, CHARLES F. LEFEVER, a citizen of the United States, and a resident of Plymouth, in the county of Wayne and 5 State of Michigan, have invented a new and Improved Razor-Stropper, of which the following is a specification.

This invention relates to machines for holding razor blades while they are being 10 stropped, and its object is to provide a simple, practical and efficient stropper which will positively retain the blades between the jaws of the blade holder while the blades are being stropped, and from which the 15 blades can be removed without danger of cutting the user.

This invention consists in combination with a handle and a frame mounted on the handle, of a pair of jaws pivoted to said 20 frame, and blade retaining devices mounted between said jaws.

In the accompanying drawings Figure 1 is a side elevation of this improved stropping machine in connection with a razor 25 strop. Fig. 2 is a rear elevation of the same. Fig. 3 is a front elevation with the holder opened to show the blade retaining devices. Fig. 4 is a vertical section on the line 4—4 of Fig. 3. Fig. 5 is a perspective 30 on a somewhat larger scale showing a blade retainer.

Similar reference characters refer to like parts throughout the several views.

In most stropping machines for the blades 35 of safety razors, reliance is placed upon the friction between the grippers or jaws of the holder and the blade to retain the blades in position, which friction depends upon the stiffness of these jaws. This necessitates 40 either a considerable amount of metal in the holder or the use of extremely rigid and high-priced material.

In the present construction, auxiliary retainers are mounted between the jaws of the 45 blade holder, which retainers will secure the blades in position without the necessity of any undue stress being placed on the holder.

In the accompanying drawings 1 is the base of a small frame having sides 2. A 50 presser-plate 3 is provided with side fingers 4 which extend outwardly on both edges of the sides 2 of the frame, as shown in Figs. 1 and 2. Downwardly extending stems 5 extend through the base 1 and small springs 55 6 on these stems normally urge the presser-

plate 3 upward against the strop 7 that extends through the frame between the presser-plate and the roller 8, which has journals on its ends that are revoluble in bearings in the sides 2 of the frame. On 60 one of the journals of this roller 8 is mounted a small gear 9 which meshes with a gear 10 on a shaft 11. Rigidly secured to this shaft 11 is the jaw 12 of the blade holder, whose inner side is shown in Fig. 3. A 65 spring 22 on this shaft engages this jaw 12 and also the pivotally mounted blade jaw 13, and normally tends to hold the jaw 13 in the position shown in dotted lines in Fig. 4, that is, substantially at right angles to the 70 jaw 12. Pivoted to the jaw 12 are small latches 14 which are adapted to be swung up and to engage the convex portions 15 of the two jaws in order to hold them in proper position when a blade 26 is placed between 75 the jaws.

Retainers 16 having slots 17 through which the headed pins 18 extend are mounted on the jaw 12 as shown in Fig. 3. These retainers have forwardly extending hooks 19 80 and small rearwardly extending fingers 20, as shown in Fig. 5, adapted to extend through the small holes 21 in the jaw 12, by which means the hooks 19 are positively positioned. In dotted lines in Fig. 3 a 85 safety razor blade 26 is shown which is provided with holes through which the hooks 19 may extend.

When it is desired to use this stropping machine, the latches 14 are swung back to 90 the position shown in Fig. 3, permitting the jaw 13 to swing forward. The retainers 16 are then placed in proper position so that the hooks 19 will be spaced so that they will pass through the holes in the blade of the 95 safety razor. By moving the retainers downward, the fingers 20 can be withdrawn from the holes 21, whereupon the retainer can be swung to any other desired position to space the hooks 19 properly for any other 100 razor blade. After being so positioned, the retainers are pushed upwardly so that the fingers 20 will engage in the proper holes 21. After the blade has been placed over the hooks, the jaw 13 is swung back as shown in 105 Fig. 4, and the latches 14 swung up as shown in Fig. 2. The strop may be slipped through between the presser-plate 3 and the roller 8 either before or after the blade is positioned.

Many blades on the market are formed with enlargements along the rear edges, which enlargements may be integral with the blades or be separate therefrom but secured thereto. The interior faces of the jaws are therefore grooved, which results in the convex portions 15 in which grooves these enlargements may rest while the blade is being stropped. At such times, the retainers are swung down parallel to the shaft 11, where they will be held with their fingers 20 in the holes 30.

The retainers 16 may be swung out until substantially parallel to each other, when the hooks 19 may be employed to engage the longitudinal projections formed at the rear corners of other blades on the market. It will therefore be seen that by forming the jaws with a series of small holes 21 to receive the fingers 20 of the retainers, this stropper can be adjusted to properly hold substantially all the safety-razor blades now on the market.

The frame comprising the base 1 and sides 2 may be attached to a handle 23 in any desired manner. One method is illustrated in the drawings, where portions of the base 1 of the frame are bent out so as to form loops 24 and 25 to receive a pin 32. A flat piece 30 of metal 27 is bent to form parallel sides with a loop in the outer end, and this holder may be slipped over the pin 32 before the presser-plate 3 and the roller 8 and shaft 11 are put in position. A handle 23 is then forced onto this doubled bar 27 and the frame will be held in proper position.

I claim.

1. In a stropping machine for razor blades, the combination with a frame comprising a base and sides, a shaft mounted in said sides, a jaw secured to said shaft and having a series of holes, a pair of blade retainers pivotally secured at one end to said jaw and having fingers at their free ends adapted to engage in said holes to position the retainers and having hooks adjacent the fingers adapted to engage razor blades, a second jaw pivotally mounted on said shaft, and means to secure the jaws together.
2. In a stropping machine for razor blades, the combination with a frame comprising a base and sides, a shaft mounted in said sides, a jaw secured to said shaft and

having a series of holes, a pair of blade retainers pivotally secured at one end to said jaw and having fingers at their free ends adapted to engage in said holes to position the retainers and having hooks adjacent the fingers adapted to engage razor blades, a second jaw pivotally mounted on said shaft, a spring to normally hold said jaws separated, and means to secure the jaws together.

3. In a stropping machine for razor blades, the combination with a frame comprising a base and sides, a shaft mounted in said sides, a jaw secured to said shaft and having a series of holes, a pair of blade retainers pivotally secured at one end to said jaw and having fingers at their free ends adapted to engage in said holes to position the retainers and having hooks adjacent the fingers adapted to engage razor blades, a second jaw pivotally mounted on said shaft, and latches to secure the jaws together.

4. In a stropping machine for razor blades, the combination of a frame, a shaft mounted therein, a pair of jaws on said shaft constituting a blade holder, and blade retainers adjustably mounted between the jaws and having hooks to engage the blades.

5. In a stropping machine for razor blades, the combination of a frame, a shaft mounted therein, a pair of jaws on said shaft constituting a blade holder, blade retainers adjustably mounted between the jaws and having hooks to engage the blades, and means to secure the jaws together to hold the razor blade in proper position.

6. In a stropping machine for razor blades, the combination of a frame, a pair of jaws pivotally mounted therein and constituting a blade holder, one of the jaws having a series of perforations, blade retainers pivoted at one end to the inner face of said perforated jaw and having fingers which are adapted to engage in the perforations, and means to secure the jaws together with a blade between them.

In testimony whereof I have signed this specification in the presence of two subscribing witnesses.

CHARLES F. LEFEVER.
